UNITED STATES PATENT OFFICE.

SOLOMON TRIPP, OF LA JUNTA, COLORADO.

SUPERHEATER.

1,141,993.

Specification of Letters Patent. Patented June 8, 1915.

Application filed July 25, 1914. Serial No. 853,198.

To all whom it may concern:

Be it known that I, SOLOMON TRIPP, a citizen of the United States, residing at La Junta, in the county of Otero and State of Colorado, have invented new and useful Improvements in Superheaters, of which the following is a specification.

My invention relates to superheaters for locomotive and other steam boilers, and its objects are to provide a superheater which is disposed in use within the boiler, and hence is directly, constantly and uniformly heated and not subjected to rapid fluctuations of temperature, a difficulty attending the use of outside heaters, which at the same time provides a lengthy course of travel for the steam, insuring the delivery of dry steam of high temperature, which may be applied to existing boilers without material, if any, alterations in the structure thereof, which is practically water-proof against leakage and operates without interfering with the free production and flow of steam or with repairs to the interior of the boiler; and which is so constructed and arranged as to insure a reliable and efficient superheating action.

The invention consists of the features of construction, combination and arrangement of parts herein fully described and claimed, reference being had to the accompanying drawing in which:

Figure 1 is a vertical longitudinal section through a locomotive boiler, showing the application of the invention. Fig. 2 is a diagrammatical top plan view partly in section, of the superheater removed from the boiler. Figs. 3 and 4 are cross sections on the lines 3—3 and 4—4 of Fig. 1.

Referring to the drawing, 1 designates the locomotive boiler embodying the usual steam dome 2, throttle 3, and steam supply pipe 4, through which the steam is discharged from the dome for supply to the cylinders through final conductor pipes 5.

The superheater is arranged in the line of feed of the steam between the stand pipe 4 and final delivery pipes 5, and includes a main conducting pipe or tube 6, which extends longitudinally within the boiler and is tapped at its inlet end 7 to receive the delivery end of the pipe 4 and is provided at its delivery end 8 with a T-connection or union 9 into which the proximate ends of the pipes 5 are tapped. As shown, the pipe 6 is provided between its inlet and delivery ends with a pair of spaced partitions 10 and 11

forming an intervening steam space or compartment 12. The diametrically opposite sides of the tube or pipe 6 are formed with openings 13 and 14, while the diametrically opposite sides of the compartmented portion 12 of said pipe are provided with openings 15 and 16. Arranged on opposite sides of the said central, longitudinally extending pipe or tube 6 are circulating or heating coils or loops 17 and 18. Each of these coils or loops 17 and 18 is of similar construction, and preferably comprises an outer, continuous longitudinally extending tube 18 and a pair of front and rear inner longitudinally extending tubes 19 and 20, the relatively outer ends of the tubes 18, 19 and 20 being apertured or provided with ports connected by suitable unions 21 and clamps 22, whereby said pipes are held assembled, the inner ends of the pipes 19 and 20 being connected with the pipe 6 by suitable clamps 23.

In practice, the central pipe 6 and the loops or coils 18 are suitably fastened within the boiler 1, and the coils 17 and 18 are arranged on opposite sides of the longitudinal center of the boiler, so as to be directly heated therefrom. It will thus be evident that all of the parts of the superheater will be contained within the boiler and maintained at a constant and uniform temperature, thus overcoming the objections to superheaters arranged externally of the boiler, which are subjected often to rapid temperature changes. The inner end 90 of the pipe 9 of the coil 17 is apertured to receive a union 24 which is also fitted within the opening 13 in the inlet end 7 of the pipe 6, while the inner end of the pipe 20 of the coil 17 is apertured to receive a union 25 which is fitted within the aperture 15 of the pipe 6. The inner end of the pipe 19 of the coil 18 is apertured to receive a union 27 which is fitted within the opening 16 of the pipe 6, while the inner end of the pipe 20 100 of the coil 18 is apertured to receive a union 28 which is fitted within the aperture 14 of the pipe 6, the said unions being threaded or otherwise secured in position and forming conductors for the flow of steam between the receiving and delivery portions of the main pipe 6 through the coils 17 and 18 in such a manner as to provide a circulating channel of comparatively great length to insure the thorough superheating of the steam in 105 its flow from the stand pipe to the cylinder. 110

From the foregoing description, it is evi-

dent that steam flowing from the stand pipe 4 first enters the inlet end 7 of the pipe 6, thence flows laterally through the union 24 to the inner end of the pipe section 19 of the 5 coil 17, thence rearwardly through said pipe into the rear end of the pipe 18 of said coil, thence forwardly through said pipe 18 and into the forward end of the pipe 20 of the coil 17, thence rearwardly through said coil 10 and through the outlet 25 into the distributing chamber 20 of the pipe 6, and thence through the union 27 and pipes 19, 18 and 20 of the coil 18 and union 28 into the delivery end 9 of the pipe 6, thence the steam 15 passes to the pipes 5 for delivery to the engine cylinders. The steam will thus be caused to flow from the delivery end of the pipe 6 through one coil, and into and through the chamber 12 into the other coil, 20 and thence through the latter-named coil back into the delivery end 8 of the pipe 6 for final discharge, the steam thus being subjected in such a circuitous passage to the intense heat of the coils, which are directly 25 inclosed within the boiler, so that the steam will be superheated to a high degree and discharged in a dry state and at a high temperature into the engine cylinders for action, the supply of dry steam of high temperature 30 and pressure to the cylinders being thereby insured. The advantage of this type of superheater in this respect will therefore be readily apparent and appreciated.

It will be observed that the construction 35 described adapts the device to be arranged directly within the boiler to receive the direct heat therefrom, and so that the super-

heater will not be subjected to rapid temperature changes, as is the case with outside superheaters. It will also be evident that the device may be arranged within the boiler 40 so that it will not be subjected to working strains, and is not therefore liable to leak or get out of order. It will be further evident that the device may be so arranged 45 that it can be installed upon any locomotive or other steam boiler without changes of any consequence, if at all, in the construction of the boiler, and that when disposed for use it will also permit the removal of the tubes 50 or other parts of the boiler for repairs and other purposes, without interference.

I claim:—

A superheater comprising a main pipe having an inlet end and a delivery end separated by an intervening compartment, coils at opposite sides of said main pipe, each comprising a continuous outer tube and a pair of inner tubes communicating at their outer ends with the ends of the outer tube, 55 connections between the delivery inner tube of one coil and the receiving inner tube of the other coil and the said compartment of the main pipe, and connections between the inner ends of the other inner tubes of the 60 coils and the inlet and delivery ends of the main pipe, respectively.

In testimony whereof I affix my signature in presence of two witnesses.

SOLOMON TRIPP.
